APPARATUS FOR CLEANING FRUIT SUCH
AS BERRIES AND THE LIKE
Wilford A. Nelson, Rte. 1, Box 175, Hubbard, Oreg.
Filed June 20, 1960, Ser. No. 37,138
2 Claims. (Cl. 15—3.11)

This invention relates to apparatus for cleaning frozen ripe berries of various types.

It is one of the principal objects of the invention to provide a novel construction into which quantities of berries are fed at one end and automatically subjected to a first stage of vibratory, gyratory, and oscillatory motion, then rolling and tumbling motion in a continuous stream of air and finally to a second or last stage of the motions mentioned as they approach and leave the discharge end of the apparatus.

By means of this invention, it is now possible to thoroughly clean voluminous quantities of berries in a days run and to deal with each berry in such a manner as to ensure effective cleaning results without damage to the berries themselves, all as is highly desired.

The common existing practice in the industry is to wash berries by means of a fluid as the berries are passed through a tank or the like. Such systems all have certain common and obvious objections in that in order to operate them a cleaning fluid must be employed which is liable to do irreparable harm to the berries being cleaned. Accordingly, I have devised a novel apparatus whereby these difficulties and objections are overcome. I accomplish this by the provision of apparatus which obviates the necessity for employing a fluid in the first instance and rely entirely upon the cleaning action of an air stream at high velocity flowing through, over, and around the berries in their uninterrupted passage through the apparatus in vibratory, gyratory rolling and tumbling motion.

Although my invention will be described herein with particular reference to a berry cleaner, it will be readily understood that its utility and application extend beyond the particular type of cleaner herein specified and comprehends the useful and novel features set forth when applied to any produce which is susceptible to a cleaning operation where dirt, dust, or the like is desired to be removed therefrom as the produce is conveyed through the various stages of the motions above referred to without material alteration to the structural features of the invention.

The foregoing and other objects and advantages which will become subsequently apparent reside in the details of construction and operation as more fully hereinafter described and claimed, reference being had to the accompanying drawings forming a part hereof, and in which:

FIGURE 1 is a side elevational view of apparatus made in accordance with my invention with fragments broken away for convenience of the illustration.

FIGURE 2 is a top plan view of FIGURE 1.

FIGURE 3 is a sectional end elevational view taken approximately along the line 3—3 of FIGURE 4.

FIGURE 4 is a fragmentary detail view on an enlarged scale.

FIGURE 5 is an end elevational view of a fixedly mounted cylinder and its relationship to a conveyor.

With continuing reference to the drawings, wherein like reference characters designate like parts, reference numeral 1 indicates generally a framework comprising elongated parallel base members 2 interconnected at their ends and provided with corner posts 3 and 4 and intermediate posts 5 and 6. To the top end of these posts 3—6 are secured two parallel beams 7 and 8. The corner posts 3 are interconnected by cross members 10 and 11

2

and to the cross member 11 is secured one end of a stationary cylinder 13 partially closed at its forward end by a semicircular plate 14 to provide a similar opening 15 and closed at its rearward end by a circular wall 16. 5 This rearward wall is provided with an opening 17 by means of which the interior of the cylinder 13 is in communication through a duct 18 with a blower fan 19, and also provided with a second opening 20 to provide a spillway directed to a conveyor generally indicated at 21, and as best shown in FIGURE 1, the cylinder is inclined rearwardly and downwardly.

A reticulated open-ended cylinder 23 is rotatably suspended concentrically within the cylinder 13 by means of belts 24 and 25 entrained respectively over driving 15 pulleys 26 and 27 and over one side of double tracks in the form of annular channel members 28 and 29 secured to and entirely encircling the cylinder 23 near the forward and rearward ends thereof. The cylinder 13 is provided with suitable openings 30 and 31 for passage of the belts 24 and 25 therethrough. Apertures 32 are also provided in the bottom peripheral wall of the cylinder near the rearward end thereof for a purpose which will become apparent as the description proceeds.

Co-operating with the belts 24 and 25 for stabilizing 25 the cylinder 23 in its rotation about its longitudinal axis within the cylinder 13, and for maintaining proper tension on the belts are respectively two pairs of rollers 34 and 35 operating respectively in the other side 37 and 38 of the annular channel track members 28 and 29. Each 30 roller as best illustrated in FIGURES 3 and 4 is carried by the inner end of a shaft 40 laterally adjustable within a slide bearing 41 and lockable thereto in adjusted positions by a set screw 42. The bearings 41 are secured to angle brackets 44 mounted upon supporting rails 46 secured at their ends to the corner posts 3 and intermediate posts 4.

The shaft 48 to which the driving pulleys 26 and 27 are secured is operatively coupled as at 49—50 to a speed reducer 51 driven by a belt 52 entrained over the 40 driving pulley of a motor 53 mounted upon a rail 54 secured at its ends to the posts 5 and 6. The blower fan 19 is driven by a belt 56 entrained over the driving pulley of a motor 57 supported within the frame 1.

The endless belt of the conveyor 21 to which buckets 50 60 are conventionally secured is entrained at its top and bottom ends over rollers secured to shafts 61 provided with sprocket wheels 62 and driven by a sprocket chain 63 entrained thereover and over the sprocket wheel 65 of a speed reducer 66 in turn driven by a belt 67 entrained over its driven pulley 68 and over one of two driving pulleys 70 of a motor 71 also mounted within the framework 1. The conveyor is supported within the framework 1 by brackets 22 secured to the side walls of the conveyor and to the beams 7 and 8.

Mounted within the framework 1 upon pairs of flexible supports 74, 75, 76, and 77 is an inclined oscillating screen assembly comprising a forward feed section F extending into the interior of the cylinders 13 and 23 through the opening 15 in the front end of the cylinder 13, and a discharge section D pivotally connected as at 80 to one end of a pitman 81 whose opposite end is connected to an eccentric 82 whose shaft 83 is journaled in a bearing block 84 mounted upon the rail 54 and driven by a belt 86 entrained over its driven pulley 88 and over the other driving pulley of the motor 70. Both screen sections F and D are in the form of trays having front and side walls and open at their rearward ends. The trays are rearwardly inclined, as shown, and pivotally interconnected by a pair of links 90 so that oscillatory motion imparted to the screen section D by the eccentric 82 will be simultaneously transmitted to the screen section F.

For convenience in feeding berries to the forward screen section F, I provide a rack 95 swingably attached as at 96 to the top end of a pair of posts 97 mounted upon the outer end of supporting arms 98 secured to and extending forwardly from the framework 1.

From the foregoing, the operation of my invention will be readily understood. With the feed and discharge screen sections F and D, rotating screen cylinder 23, conveyor 21 and blower fan 19 all in operation by their respective motors and drive connections, a tray of frozen berries is placed upwardly against the underside of the rack 95 when the rack is in a horizontal position. The tray and rack are then swung upwardly into the position shown in FIGURE 1 where the rack will come to rest against a limit stop 99. In approaching this position the berries will spill onto the feed section F and partake of the vibratory, gyratory and oscillatory motion imparted to it as aforesaid. And such motion will cause the berries to disseminate over the feed section and foreign matter to be shaken from them as they gravitate into the rearwardly inclined rotating screen cylinder 23 where they are subjected to further cleaning by the rolling and tumbling action imparted to them and also by the air stream coming from the blower fan 19. Foreign matter shaken from the berries is picked up by the air stream and blown out through the open end of the cylinder 23 and that which sifts through the walls of the screen cylinder is blown out through the openings 32 in the bottom wall of the cylinder 13. From the screen cylinder the berries gravitate through the opening 20 in the end wall 16 of the cylinder 13 and onto the conveyor 21 from the top end of which they are deposited onto the discharge screen section D to partake of its vibratory, gyratory, and oscillatory motion as they gravitate out through the open end of said section and into proper containers or the like in a thoroughly cleaned and unharmed condition. It is to be noted that there are no baffles or any other obstructions which the berries might impinge against, nor any whipping air turbulence to damage the berries as they travel through the apparatus.

While I have shown a particular form of embodiment of my invention, I am aware that many minor changes therein will readily suggest themselves to others skilled in the art without departing from the spirit and scope of the invention. Having thus described my invention what I claim as new and desire to protect by Letters Patent is:

1. Apparatus for cleaning foreign matter from the exterior surfaces of berries and the like, comprising in combination a framework having a forward end and a rearward end, an imperforate cylindrical housing fixedly mounted within the framework at the forward end thereof and rearwardly inclined relative thereto, said housing having a front wall and a rear wall and an opening in the front wall and a first and second opening in said rear wall in the bottom portion thereof, a reticulated open ended cylinder of uniform diameter throughout its length rotatably mounted within said housing in concentric spaced relation thereto, air pressure generating means in open communication through said first opening in the rear wall of said fixed housing with the interior thereof and with the interior of said reticulated cylinder, motor means operatively connected to said reticulated cylinder for rotating the same, a rearwardly inclined resiliently supported reticulated feed tray at the forward end of said framework extending through the opening in said front wall of said housing and into the forward end of said reticulated cylinder, a rearwardly inclined reticulated discharge tray resiliently supported within said framework at the rearward end thereof, means interconnecting said feed tray and said discharge tray, motor driven eccentric means mounted within said framework and connected to said discharge tray for imparting oscillatory motion simultaneously to both of said trays, and conveyor means having a top end and a bottom end communicating at its

bottom end with the interior of said reticulated cylinder and the interior of said fixed housing through said second opening in the rear wall thereof to receive berries gravitated from said reticulated cylinder and adapted at its top end to discharge the berries onto said discharge tray, whereby the berries will gravitate while in vibratory, gyratory, and oscillatory motion from the feed tray into said rotatable reticulated cylinder and be subjected therein to rolling and tumbling motion in an air stream from said air pressure generating means and to gravitate from said cylinder onto said conveyor and from the conveyor onto the discharge tray and be subjected to a second stage of vibratory, gyratory, and oscillatory motion as they gravitate toward the discharge end of said discharge tray.

2. Apparatus for cleaning foreign matter from the exterior surfaces of berries and the like, comprising in combination a framework having a forward end and a rearward end, an imperforate cylindrical housing of uniform diameter throughout its length fixedly mounted within the framework at the forward end thereof and rearwardly inclined relative thereto, said housing having a front wall and a rear wall and an opening in the front wall and a first and second opening in said rear wall in the bottom portion thereof, said housing having openings in the cylindrical wall thereof, power driven belts extending through certain of said openings, a reticulated cylinder of uniform diameter throughout its length open at both of its ends and rotatably suspended within said cylindrical housing by said belts, rollers carried by said framework extending through other of said openings in the cylindrical wall of said housing and at all times in rolling contact with said reticulated cylinder, air pressure generating means in open communication through said first opening in the rear wall of said fixed housing with the interior thereof and with the interior of said reticulated cylinder, a rearwardly inclined resiliently supported reticulated feed tray at the forward end of said framework extending through the opening in said front wall of said housing and into the forward end of said reticulated cylinder, a rearwardly inclined reticulated discharge tray resiliently supported within said framework at the rearward end thereof, means interconnecting said feed tray and said discharge tray, motor driven eccentric means mounted within said framework and connected to said discharge tray for imparting oscillatory motion simultaneously to both of said trays, and conveyor means having a top end and a bottom end communicating at its bottom end with the interior of said reticulated cylinder and the interior of said fixed housing through said second opening in the rear wall thereof to receive berries gravitated from said reticulated cylinder and adapted at its top end to discharge the berries onto said discharge tray, whereby the berries will gravitate while in vibratory, gyratory, and oscillatory motion from the feed tray into said rotatable reticulated cylinder and be subjected therein to rolling and tumbling motion in an air stream from said air pressure generating means and to gravitate from said cylinder onto said conveyor and from the conveyor onto the discharge tray and be subjected to a second stage of vibratory, gyratory, and oscillatory motion as they gravitate toward the discharge end of said discharge tray.
